UNITED STATES PATENT OFFICE.

VINTON E. SISSON, OF CHICAGO, ILLINOIS, ASSIGNOR TO WALTER P. MURPHY, OF CHICAGO, ILLINOIS.

REINFORCED SHEET-STEEL END WALL FOR RAILWAY-CARS.

1,324,569.

Specification of Letters Patent.

Patented Dec. 9, 1919.

Application filed December 10, 1915. Serial No. 66,127.

To all whom it may concern:

Be it known that I, VINTON E. SISSON, a citizen of the United States, residing at Chicago, in the county of Cook and State 5 of Illinois, have invented certain new and useful Improvements in Reinforced Sheet-Steel End Walls for Railway-Cars, of which the following is a specification.

My invention relates to the construction 10 of railway cars, more particularly box freight cars, and the invention has for its principal object to provide a sheet metal end wall for a railway car which will be reinforced in a novel manner so that it will 15 be capable of withstanding the cargo thrusts and other stresses and impacts to which the end wall of a car is subjected when in service.

A further object is to provide a sheet steel 20 end wall for a railway car composed of overlapping panels formed with reinforcing ribs or off-sets which are so disposed on the panels that they may be formed by a cold pressing process. Because of this feature 25 the cost of manufacturing is considerably reduced.

The invention consists in the several constructions, arrangements and combinations to be hereinafter described and claimed for 30 carrying out the above stated objects, and such other objects as will appear in the following description.

The invention is illustrated, in a preferred embodiment, in the accompanying 35 drawings wherein—

Figure 1 is an end elevation of the superstructure of a box car provided with the sheet metal reinforcing wall of my invention.

Fig. 2 is a fragmentary plan view of the 40 end of the car with the roof boards removed.

Fig. 3 is a fragmentary side elevation of the end of the car.

Fig. 4 is a vertical sectional view taken on line 4-4 of Fig. 1.

Fig. 5 is a fragmentary sectional plan on line 5-5 of Fig. 1.

Fig. 6 is a fragmentary end elevation of the car showing a modified construction in which the reinforcements run vertically instead of horizontally.

Fig. 7 is a sectional view on line 7-7 of Fig. 6, and

Fig. 8 is a sectional plan on line 8-8 of Fig. 6.

Like characters of reference designate like parts in the several figures of the drawings.

Referring to the drawings, the corner posts of the car are shown at 10, the end sill at 11, the flooring at 12 and the side sheathing at 13. It will be understood that my invention is not limited in its application to a car of the particular type shown and described.

The end wall of the car consists of a plurality of sheet metal panels which are preferably in horizontal arrangement one above the other with their edges overlapping. I have shown three of these panels, designated 14, 15 and 16, respectively. The upper portion of the upper panel 14 is preferably 65 bent over on oblique lines so as to form the tapering flanges 17 shown more particularly in Fig. 2. These flanges support the purlins 18 and the ridge pole 19, the connection of the flanges with the latter being reinforced preferably by a plate 20. The outer ends of the flanges 17 rest upon and are riveted to angular brackets 21 secured to the side plates 22 of the car. 23 are filler blocks 70 interposed between the purlins and between the purlins and the ridge pole, closing the spaces above the flanges 17 and below the roof boards 24. The end of the car has the usual fascia plate 25. It will be seen that the frame members of the roof are supported 75 directly on the upper panel of the end wall. The flanges 17 take the place of the usual end plate. The fact that these flanges increase in width toward the sides of the car 80 makes them particularly adaptable as a substitute for the end plate of the car since this configuration makes them unusually strong to check weaving strains in the car roof. Each of the three panels is formed at its lower edge with a hollow offset or rib 26. 85 This offset portion of the panel overlaps the upper edge of the adjacent panel which is secured thereto by two lines of rivets 27 lying on opposite sides of the rib. The panels are formed on their vertical edges 90 with angular flanges 28 which are secured, for example, by bolts 29 to the corner posts 10 of the car. 30 is an angular connecting member, one leg of which is riveted to the lower edge of the lower panel 16 and the other leg to the end sill 11 which latter is 95 preferably in the form of a channel. The flanges 28 preferably terminate just short

of the offset portions of the panels. Accordingly the offset portions extend across the end only of the car, the flanges 28 having been omitted in the region of the offsets. 5 This construction permits the pressing of the offsets in the sheet while cold. The lower corners of the panels are pressed out, as indicated at 31, so that each panel will overlap the panel next below it. 32 are attaching plates riveted to the flanges 28 of the upper panel and secured to the side plates 22 of the car. 33 are angle strips secured preferably to the side girders 34 of the car and overlapping and riveted to the lower 15 edges of the panels 14, 15. The connection of the panel 16 to the sills is reinforced by gussets 35 which are bent under the car as indicated at 36 and secured to the side sills 37. The side sills 37 are of Z-shape in cross- 20 section.

The end wall structure above described is preferably provided with a wooden inner lining 38 which is spaced away from the sheet metal wall by spacing strips 39, the 25 strips and the lining being secured to the metal wall by bolts 40 which pass through the overlapped portions of the panels.

In Figs. 6 to 8 inclusive, I have shown a modification in which the reinforcements 30 run vertically of the structure instead of horizontally. The end consists of a plurality of vertically arranged panels 41, 42, 43, 44. Each panel is provided at its lower edge 35 with a flange 45 riveted to the end sill 11^a, one flange overlapping the next adjacent flange, as indicated at 46. The panels are provided at their upper edges with flanges 47 overlapped and riveted together at 48 so that they form preferably a supporting 40 member for the ridge pole and purlins which is preferably narrowest at the ridge pole and increases in width toward the eaves, as in the construction shown in the first five figures. The panels 41, 44 are 45 formed with flanges 49 which overlap and are secured to the corner posts 10^a by bolts 50. Three of the panels, that is panels 42, 43 and 44, are formed with hollow offsets 51, 52, 53 on the vertical edges overlapping 50 the adjacent panels, respectively. The panels are secured together by double lines of rivets 54 on opposite sides of each hollow offset. The offset portions of the panel fall short of the edges of the body portions 55 of the panels as in the other construction.

The form of the invention illustrated in Figs. 6, 7 and 8 is not claimed specifically herein, the specific features of this form of the invention being claimed in my copending application, Serial No. 312,898, filed July 24, 1919.

I claim:

1. An end structure for a railway car comprising a plurality of sheet metal panels, the edges of which overlap each

other, one of said overlapping edges, in each case, being formed with a pressed out rib and the corresponding edge of the other panel being secured to the first named panel on opposite sides of said rib, said panels 70 being formed on the edges at right angles to the overlapped edges with angular attaching flanges which terminate short of said ribs.

2. An end structure for a railway car 75 comprising a plurality of sheet metal panels in horizontal arrangement one above the other, the edges of which overlap each other, one of said overlapping edges, in each case, being formed with a pressed out 80 rib and the corresponding edge of the other panel being secured to the first named panel on opposite sides of said rib; said panels being formed on their vertical edges with angularly disposed attaching flanges which 85 terminate adjacent said ribs at a point above the lower edges of said panels.

3. An end structure for a railway car comprising a plurality of sheet metal panels in horizontal arrangement one above the other, the edges of which overlap each other, one of said overlapping edges, in each case, being formed with a pressed out 90 rib, and the corresponding edge of the other panel being secured to the first named panel 95 on opposite sides of said rib in combination with the end sill of the car, and an angular member, one leg of which is secured to said end sill and the other to the lowermost of said panels on opposite sides 100 of the rib therein.

4. An end structure for a railway car comprising a plurality of sheet metal panels in horizontal arrangement one above the other, the edges of which overlap each other, one of said overlapping edges, in each case, being formed with a portion which terminates 105 within the edges of the end structure and provided with a pressed out rib and the corresponding edge of the other panel being 110 secured to the first named panel on opposite sides of said rib, angular flanges on the vertical edges of said panels in combination 115 with the end sill and side sills of the car, an angular member, one leg of which is secured to said end sill and the other to the lower panel of the end wall, and gussets which are attached to the angular member and project under the car and are secured to the side sills.

5. An end structure for a railway car comprising a plurality of sheet metal panels in horizontal arrangement one above the other, the edges of which overlap each other and are secured together, and angular flanges on the vertical edges of said panels in combination 125 with the end sill and side sills of the car, an angular member, one leg of which is secured to said end sill and the other to the lower panel of the end wall, and gussets 130

which are attached to the angular member and project under the car and are secured to said side sills.

6. An end structure for a railway car comprising a plurality of sheet metal panels, the edges of which overlap each other, one of said overlapping edges, in each case, being formed with a pressed out rib, attaching devices for securing the overlapping edges of said panels together on opposite sides of said ribs, and wood spacing strips and a wood lining secured to the inner side of said sheet metal wall by means of certain of the aforesaid attaching devices.

15. 7. A railway car end panel having an offset rib near one edge, and having flanges along the adjacent edges, the flanges terminating short of the rib.

8. An end construction for a railway car, comprising a plurality of sheet metal panels having overlapping edges, one of said overlapping edges being formed with a pressed rib open at opposite ends and terminating within the edges of the car end, a lining secured to the inner side of said sheet metal wall, and means for securing said lining to and spacing it from said sheet metal wall.

9. In combination with the framing of a railway car, a sheet metal end structure for 30 the car comprising two panels, the edge of one of which overlaps the other panel and is

formed with a hollow rib open at opposite ends, the edges of the panels transverse to the aforesaid edges being formed with flanges which overlap one upon the other 35 and are secured to the framing of the car, and said channel portion of one panel terminating within the plane of said flanges.

10. In combination with the framing of a railway car, a sheet metal end structure for 40 the car comprising metal panels having their adjacent edges overlapped and having their edges transverse to the aforesaid edges provided with attaching flanges, a portion of the overlapping edge of one sheet stopping 45 short of the plane of said attaching flanges and formed with a reinforcing rib which extends across said short portion of said overlapping edge.

11. An end structure for a railway car 50 comprising a plurality of sheet metal panels, the edges of which overlap each other, one of said overlapping edges in each case being formed with a rigidifying rib and the corresponding edge of the other panel being secured to the first named panel on opposite sides of said rib, said panels being formed on the edges at right angles to the overlapped edges with angular attaching flanges which terminate short of said ribs.

VINTON E. SISSON.
